GOLF CLUB CLEANING DEVICE

John H. Downing, 3868 S. Beachview Drive,
Willoughby, Ohio

Filed June 29, 1959, Ser. No. 823,522

1 Claim. (Cl. 15—105)

This invention relates to a cleaning device for golf clubs and more particularly to a device for cleaning off mud and dirt from the driving face of the head of such clubs.

Under normal use the driving face of a golf club head often becomes encrusted and covered with mud and dirt which seriously interferes with effective use of the club. Various golf club head cleaning devices have been devised, but are too large and bulky to be conveniently carried on the golf course, and are ineffective for thoroughly cleaning the club heads, such prior devices failing completely to enable the user to thoroughly clean mud and dirt out of the channels or grooves in the driving face of the club head. Other of such prior cleaning devices are too small for effective use.

It is an object of the present invention to provide a cleaning device for cleaning the driving face of golf club heads and particularly for cleaning the grooves formed in such driving faces.

A further object of the invention is to provide a golf club head cleaning device that is small, compact, light in weight, and which may be carried easily and inconspicuously by a user when playing golf.

A further object of the invention is to provide a golf club cleaning device that is simple to operate, inexpensive to manufacture, and is very effective in operation.

Briefly the foregoing objects are accomplished by the provision of a golf club cleaning device including an elongated handle having a scraper blade at one end and a brush depending from the handle adjacent the other end thereof. The scraper blade may form an end extension of the handle and may extend downwardly from and outwardly of the same side of the handle from which the brush depends. A pointed blade or nib may be formed on the other side of the handle at the juncture of the handle and scraper blade. With this construction, the driving face of the golf club head may be easily cleaned by scraping off the mud and dirt therefrom with the scraper blade and brushing off any remaining dirt with the brush. If any dirt remains in the grooves of the driving face, it can be quickly and easily removed with the pointed spur on the back of the handle. Additionally, the device is small, compact, light in weight, and may be easily and inconspicuously carried by the golfer.

Other objects and advantages of the invention will be apparent from the following description, taken in conjunction with the drawings, wherein:

Fig. 1 is a perspective view of a cleaning device constructed in accordance with the invention;

Fig. 2 is a top plan view of the device shown in Fig. 1;

Fig. 3 is a side elevational view of the device shown in Fig. 1; and

2

Fig. 4 is a left end view of the device shown in Fig. 3.

Although the invention is shown and described herein with reference to the cleaning of the driving face of the head of a golf club, it may be used for cleaning any substantially planar surface and particularly a planar surface having grooves in the face thereof.

Referring to the drawings, there is shown a cleaning device A constructed in accordance with the invention and comprising an elongated handle 10 having a scraper 10 blade 12 at the one end and a brush 14 at the other end thereof. In the preferred form, the handle, in transverse section, may be of an inverted U-shape for purposes of strength and lightness in weight.

The scraper blade 12 is preferably of triangular shape having a scraping edge 13 and depends downwardly and outwardly from the end of the handle as shown in Fig. 3. Although the scraper blade is shown as depending at an angle from the end of the handle, it may extend straight out from the handle and form a linear extension thereof.

The brush 14 in the preferred embodiment is formed of a synthetic plastic material, although any suitable type of brush material may be used. The brush 14 is secured in a depending portion 16 to position the brush outwardly from the handle for more effective use.

Disposed on the top of the handle at the juncture of the scraper blade 12 and the handle 10 is a pointed spur or nib 18 which may be used to clean out the grooves in the driving face of the club head. Although the nib 18 is shown as shaped in the form of a triangular pyramid, it may be of any suitable shape having a sharp spur or point at the outer end thereof. Although the spur 18 is shown as positioned at the juncture of the handle 10 and the scraper blade 12, it may be disposed at any suitable position on the handle.

An aperture 20 may be formed in the handle, as shown, for receiving a cord or the like with which the device may be attached to the golfer's belt, golf cart, or golf bag.

Although the scraper blade 12 is shown as being of triangular shape, it may be of any suitable shape that will enable the user to effectively scrape the dirt off the driving face of the club.

The terms and expressions which have been employed are used as terms of description, and not of limitation, and there is no intention, in the use of such terms and expression, of excluding any equivalents of the features shown and described or portions thereof, but it is recognized that various modifications are possible within the scope of the invention claimed.

Having thus described my invention, I claim:

50. A device for cleaning the head of a golf club comprising an elongated handle, a flat scraper blade disposed at one end of said handle, a brush secured to and depending transversely from the handle adjacent the other end thereof, said scraper blade forming an extension of the handle and extending downwardly from and outwardly of that side of the handle from which the brush depends, a pointed spur on the handle for cleaning the driving face of the golf club, said spur projecting from that side of the handle opposite the first named side adjacent the juncture of the handle and the scraper blade, said spur being disposed within the longitudinal horizontal plane of the handle and forming a continuation of the handle.
